J. G. NORTON.

METHOD OF TREATING BLANKS.

FILED JAN. 30, 1919.

Fig. 3.

INVENTOR.

James G. Norton

UNITED STATES PATENT OFFICE.

JAMES G. NORTON, OF QUINCY, MASSACHUSETTS, ASSIGNOR TO UNITED SHOE MACHINERY CORPORATION, OF PATERSON, NEW JERSEY, A CORPORATION OF NEW JERSEY.

METHOD OF TREATING BLANKS.

Application filed January 30, 1919. Serial No. 274,042.

To all whom it may concern:

Be it known that I, JAMES G. NORTON, a citizen of the United States, residing at Quincy, in the county of Norfolk and State 5 of Massachusetts, have invented certain Improvements in Methods of Treating Blanks, of which the following description, in connection with the accompanying drawings, is a specification, like reference characters 10 on the drawings indicating like parts in the several figures.

This invention relates to a method of treating blanks such for example as sole or heel lift blanks and is herein described as a 15 method of treating heel lift blanks preparatory to incorporating them in the heels of boots and shoes.

Heel lift blanks are commonly cut out of pieces of hide; and, owing to the fact that 20 hides vary in thickness at different localities, the heel lift blanks vary from one another in the same dimension, and a large part of them vary individually in thickness, that is, they are thicker at one point than at another. Before the blanks are incorporated 25 in the heels it is desirable that each one should be of uniform thickness throughout to fit it for the subsequent operations by which it is made into the finished heel. Preferably the lifts after being made of 30 uniform thickness are separated into groups, each member of which is of the same thickness before being passed to the heel making machine. Specifically, the standard of 35 measurement ordinarily used is an "iron" which equals one forty-eighth of an inch; and the groups may be made up respectively of lifts the members of which have a thickness 5 irons, $5\frac{1}{2}$ irons, 6 irons, etc.

Hitherto it has been customary to run all 40 the lifts through a skiving machine which evens each blank and then to sort them into groups, each member of which has the same thickness. A large number of the blanks, 45 however, are originally of uniform thickness throughout, or at least nearly enough so to be built into heels, and any skiving of these blanks results in a waste of material. The sorting of the lifts is commonly made in accordance with their thickness at a selected 50 point on the assumption that the work of the skiving machine is perfect. This assumption is not always reliable, however,

and it is therefore desirable in some cases that the lifts be tested for uniformity in 55 thickness before being used.

In carrying out the method of the present invention with reference to the thickness dimension of blanks, the heterogeneous collection of blanks is first tested one by one 60 to determine for each blank the difference between the thickness of the thinnest and that of the thickest point throughout the whole blank or throughout a selected locality thereof. All those blanks which have no 65 such difference or substantially none and are therefore of uniform thickness throughout are placed in one group, and all those which have a difference in thickness are sorted into groups the members of which have approximately 70 the same amount of difference in thickness.

The blanks having been separated in the manner described above, the groups composed of uneven lifts are then treated in 75 succession by having the members thereof reduced to an even thickness, for example, by running them through a skiving machine which is set once for each group. After having been skived they may be 80 tested again for unevenness, if desired, and any found to be uneven may be reskived. These blanks, retested and reskived as far as necessary, are then placed with the blanks of the first group each member of which was 85 found by test to be of uniform thickness. Accordingly, they are in proper condition to be made up into heels. The lifts, however, differ from one another in thickness. They are preferably next 90 sorted into groups the members of which have the same uniform thickness. By this method of treatment, the waste in material and labor which has formerly resulted from running through the skiving machine 95 blanks which were of substantially uniform thickness is avoided, and uniformity in thickness of each lift is finally ensured.

Referring now to the accompanying drawings,—

Fig. 1 shows in cross-section three members of one of the groups into which blanks of non-uniform thickness are sorted preparatory to being skived;

Fig. 2 shows similarly three members of another group the thickness-difference of

which is less than that of the members of the group shown in Fig. 1, and

Fig. 3 shows the principal parts of a skiving machine adapted to even blanks 5 such as are shown in Figs. 1 and 2, the thickness-difference of which is known.

The blanks are died out indiscriminately from pieces of leather with the result that the blanks, as they are thrown into a basket 10 or other receptacle, form a heterogeneous collection, the problem being to separate those which are uniform in thickness throughout from those which are not, to reduce without waste each of the latter to a 15 substantially uniform thickness throughout and then to sort all of the blanks into groups each member of which has the same uniform thickness.

The blanks are first tested one by one for 20 variation in thickness with reference particularly to the edge portion or part of the edge portion of the blank, those which have a variation being placed in a series of groups in accordance with the amount of this variation 25 or thickness-difference. For example, all which have a thickness-difference of from one-half to one iron may be placed in one group, those which have a thickness difference of from one and one-half to two irons 30 in another group, etc. Three members each of two of such groups are shown in Figs. 1 and 2, those of Fig. 1 having a thickness-difference of say one iron and those of Fig. 2 35 having a thickness-difference of say one-half an iron. It should be noted that the absolute thickness of the members of the groups is immaterial and may vary greatly. Although this separation of the blanks, on the one hand into a group each 40 member of which has no variation in thickness, and on the other hand into a series of groups each member of which does have variation, may be accomplished by the use of a gage, caliper or other hand tool it will 45 preferably be carried out commercially by the use of an automatic machine.

The blanks having been separated into the groups which have been described above, those groups in the members of which variation 50 in thickness is present are next treated in succession by having their individual members operated upon to remove the variation. This operation may be carried out in any suitable manner, as for example by 55 running them through a skiving machine which is set once for the members of each group.

In Fig. 3 there are shown the principal 60 parts of a machine by which this may be accomplished, taking one group at a time and finishing the members thereof before proceeding with the members of the next group. A fixed member 5 carries a plurality of 65 spring-pressed rollers 7, said fixed member having a plane lower face with which the

cutting edge of a knife 9 is maintained parallel, said knife being fast to a carrier 11 which is vertically adjustable in proper guideways by means of a screw bolt 13 threaded through a portion of the fixed 70 member 5 and having a head rotatable in but held from longitudinal movement with respect to the knife carrier 11. In practice the knife will be adjusted for each group of blanks of non-uniform thickness so that the 75 distance from the edge of the knife to the under surface of the fixed member 5 will be equal to the thickness-difference of the particular group to be operated upon, and then that group will be run through the machine 80 one by one. Each blank may be placed upon the top of a plunger 15 which is normally in lowered position and has mounted therein a driven feed roll 17. The plunger is then raised through a spring 18 by a cam 21 into 85 the position shown and held there, this position being determined by the thickness of the blank at its thickest point. Power is then applied to the driven roll 17 to feed the blank to the knife. In order to facilitate the feeding of the blank the plunger may carry a plurality of idle rolls 23, or these rolls may also be driven with the roll 17; and, in order to facilitate an adjustment of the knife, a 90 pointer 25 fast to the fixed member may co-operate with a scale marked on the knife carrier.

The evened lifts as they leave this machine may be received in the same receptacle in which the first group of blanks of even 100 thickness was placed. All of the blanks are at this stage individually of uniform thickness and are accordingly in proper condition to be made up into heels. Before being passed to the heel making machines, they 105 may be sorted, preferably by means of an automatic machine, into groups each member of which has the same uniform thickness.

Although, as stated above, the skived lifts 110 may be added directly after the skiving operation to the group of lifts each member of which is of uniform thickness, it may be desirable with some kinds of stock or where particularly fine shoes are being manufactured, to retest the skived lifts for uniformity in thickness and to reskive such of them as are found not to be uniform in this dimension so that the substantial uniformity 115 in thickness of all the lifts is absolutely ensured; and with regard to the first step of the method, which comprises sorting the even from the uneven blanks, if a measuring tool is used, which indicates the extent of the thickness of each blank and not merely the extent of the variation in the thickness, it may be found desirable to sort the blanks 120 which have no variation immediately into groups in accordance with their thicknesses, and to add to these groups the other blanks 125 130

after they have been passed through the skinning machine or have otherwise been made uniform.

For the purpose of illustration blanks of 5 non-uniform thickness have been shown which are wedge-shaped in cross-section; but it should be understood that neither the shape nor the nature of the blanks, nor the characteristic in accordance with a variation 10 in which the blanks are treated is material to the invention in its broader aspects. The machine which has been briefly described is not herein claimed but forms the subject-matter of application Ser. No. 428,260, filed 15 in my name.

Having thus described my invention, what I claim as new and desire to secure by Letters Patent of the United States is:

1. The method of treating a plurality of 20 blanks which comprises measuring them for the amount of variation in a selected characteristic at different localities, sorting the blanks into groups in accordance with such variation and operating upon the blanks, 25 group by group, to remove the said variation in the selected characteristic and render each blank substantially uniform with respect to the selected characteristic.

2. The method of treating heterogeneous 30 blanks which comprises determining the amount of variation in thickness at different localities on each blank, sorting the blanks into groups in accordance with the amount of this variation so that all blanks having 35 substantially the same amount of variation in thickness are collected into the same group, and then operating upon the blanks of each of the aforesaid groups, taking each group separately, to remove the said individual variation and render each blank substantially uniform in thickness.

3. The method of treating a plurality of

blanks the members of which are partly of substantially uniform and partly of non-uniform thickness which comprises separating 45 the blanks of substantially uniform thickness from those which are non-uniform, measuring the non-uniform blanks for the amount of variation in thickness, sorting the measured blanks into groups in accordance 50 with such variation, and operating upon these blanks group by group to remove said variation and render each blank of substantially uniform thickness.

4. The method of treating a plurality of 55 blanks the members of which are partly of substantially uniform and partly of non-uniform thickness which comprises separating the blanks of substantially uniform thickness from those which are non-uniform, 60 measuring the non-uniform blanks for the amount of variation in thickness, sorting the measured blanks into groups in accordance with such variation, operating upon these blanks group by group to remove said variation and render each blank of substantially 65 uniform thickness, and finally sorting all of the blanks into groups the members of which have the same thickness.

5. The method of treating a plurality of 70 blanks which comprises measuring them for the amount of variation in thickness between selected localities, sorting the blanks into groups in accordance with such variation, operating upon the blanks group by 75 group to remove the said variation and render each blank of substantially uniform thickness, and sorting the blanks into groups the members of which have the same thickness.

In testimony whereof I have signed my name to this specification.

JAMES G. NORTON.
